PAIR OF SPECTACLES

Frank W. Lindblom, Warwick, R. I.

Application November 30, 1956, Serial No. 44,000

Term of patent 14 years

(Cl. D57—1)

FIG. 1

FIG. 2

FIG. 3

FIG. 4

Fig. 1 is a front elevational view of a pair of spectacles showing my new design;

Fig. 2 is a rear elevational view thereof;

Fig. 3 is a top plan view thereof; and

Fig. 4 is an end elevational view thereof.

The dominant feature of the design resides in the portion shown in full lines.

I claim:

The ornamental design for a pair of spectacles, substantially as shown and described.
